UNITED STATES PATENT OFFICE.

BERTON M. MATHIAS, OF MINNEAPOLIS, MINNESOTA.

ROD-SPlicing CLAMP.

1,252,711.

Specification of Letters Patent.

Patented Jan. 8, 1913.

Application filed May 24, 1916. Serial No. 99,684.

To all whom it may concern:

Be it known that I, BERTON M. MATHIAS, a citizen of the United States, and a resident of Minneapolis, in the county of Hennepin 5 and State of Minnesota, have invented certain new and useful Improvements in Rod-Splicing Clamps, of which the following is a specification.

One object of my invention is to provide 10 means for splicing rods or wire rope together in such a manner as to have the full strength of the splice available without motion.

Another object of my invention is to provide 15 parts on the clamp engaging together, so that the stress in one saddle member is imparted to the other member, independent of the clamping bolts.

Another object of my invention is to provide 20 yielding studs which act as a wedge or incline, keeping the lugs in positive contact.

Another object of my invention is to provide 25 an intermediate grip to transfer the stress in one of the saddles directly, and undiminished to the other saddle.

Another object of my invention is to provide 30 corrugations encircling the clamping members to increase the gripping and holding means.

With these and incidental objects in view 35 the invention consists of certain novel features of construction and combination of parts, the essential elements of which are hereinafter described with reference to the drawing which accompanies and forms a part of this specification.

In the drawings Figure 1 is a side view of 40 a clamp embodying my invention, and Fig. 2 is a side elevation of the same.

Fig. 3 is an end view of a modification of 45 the clamp, and Fig. 4 is a side elevation of the same.

Fig. 5 is an end view of my preferred style of clamp, and Fig. 6 is a side elevation of 50 the same.

Fig. 7 is an end view of a still further modification of the clamp, and Fig. 8 is a side elevation of the same.

In my preferred construction, as shown in 55 Figs. 5 and 6, 1 and 2 are saddles having lugs 3 and 4, respectively, to engage with the spaces between corresponding lugs 5 and 6, respectively, on the intermediate grip.

Studs 7 and 8, securely mounted in the 60 saddles 1 and 2, respectively, are adapted to

engage with the wedges 9 and 10, carried by the saddles 1 and 2, respectively, so as to maintain these wedges in intimate contact at the point 11.

The saddles are preferably constructed so 60 as to be drawn together by U bolts 12 and 13, although it is obvious that they may be drawn together by ordinary bolts.

A modification of this device is shown in 65 Figs. 1 and 2, in which the wedges 9 and 10 and the corresponding yielding studs 7 and 8 are omitted.

In Figs. 3 and 4 is shown a modification, 70 in which the wedges 9 and 10 are utilized with the yielding studs 7 and 8, but the lugs shown in the other two modifications are omitted.

In the clamp shown in Figs. 7 and 8, a simple and cheaper construction is devised, 75 and two simple clamps 13 and 14 have side projections 15 and 16, respectively, so that the U bolts holding the two together will bind the two individual clamps together and make them serve as a single clamp.

In the modification shown in Figs. 4 and 80 8, the rods 17 and 18 are clamped directly together, while in the modification shown in Figs. 2 and 6, intermediate clamps are used to provide a larger gripping surface.

In any of the devices it is evident that 85 the clamping surfaces of the saddles and the intermediate grip may be corrugated, as shown at the point 19 in Figs. 2 and 4.

While I have described my invention and 90 illustrated it in several designs, I do not wish it understood that I limit myself to these constructions, as it is evident that the application of my invention may be varied in many ways within the scope of the following claims.

Claims:

1. In rod splicing clamps the combination of a clamping member, wedge shaped lugs on said clamping members and yielding studs mounted in said clamping members. 100

2. In rod splicing clamps the combination of two saddles, lugs with intermediate depressions on each of said saddles, an intermediate grip having lugs and intermediate 105 depressions on either side thereof adapted to engage with said saddles, yielding studs mounted in said saddles, engaging lugs on each of said saddles having one surface thereof perpendicular to the axis of said 110

saddles, and the opposite surface thereof at an angle to said perpendicular surface, said surface at an angle in each of said saddles being adapted to be engaged with said yielding studs in the other of said saddles.

5 3. In rod splicing clamps the combination of a clamping member, wedge shaped

lugs on said clamping member and yielding studs mounted in said clamping member, and means associated with said clamping member for clamping rods or ropes to be spliced therebetween.

10 BERT M. MATHIAS.
